UNITED STATES PATENT OFFICE.

ANTONIO KERSUL, OF NEW YORK, N. Y.

APPARATUS FOR LOWERING LIFE-BOATS.

SPECIFICATION forming part of Letters Patent No. 713,889, dated November 18, 1902.

Application filed July 5, 1902. Serial No. 114,476. (No model.)

To all whom it may concern:

Be it known that I, ANTONIO KERSUL, a citizen of Austria-Hungary, residing in New York, borough of Manhattan, in the State of New York, have invented certain new and useful Improvements in Apparatus for Lowering Life-Boats, of which the following is a specification.

The object of this invention is to provide means whereby a life-boat on shipboard can be conveniently and quickly lowered, the boat when not in use being effectively protected by a suitable cover and securely retained in upright position upon the deck of the vessel.

For this purpose the invention consists of an apparatus for lowering life-boats comprising two davits mounted rotatably upon the vessel, one at each end of the life-boat, chocks on the vessel for supporting the life-boat, and suitable tackle connected with said life-boat, and with the davits for automatically turning the latter when the life-boat is released from the chocks.

The invention consists, further, of certain combinations of parts and details of construction, which will be fully described hereinafter and finally pointed out in the claims.

In the accompanying drawings, Figure 1 is a side elevation of a life-boat, together with my improved apparatus for lowering the same. Fig. 2 is a top view, the cover of the life-boat being removed. Fig. 3 is a top view with the boat swung outwardly and supported by the davits. Fig. 4 is an end elevation with the boat in inward position supported on the vessel, as in Fig. 1. Fig. 5 is a vertical section on line 5 5, Fig. 3. Fig. 6 is a side elevation, on a larger scale, of one of the davits and tackle. Fig. 7 is a vertical section, on a larger scale, on line 7 7, Fig. 2. Figs. 8 and 9 are respectively a side elevation and a bottom view of one of the movable chock-blocks, and Fig. 10 is a vertical longitudinal section centrally through the life-boat and its cover.

Similar letters of reference indicate corresponding parts.

Referring to the drawings, A indicates a life-boat, which is of the common or any suitable construction.

B is the hull of the vessel, upon which the life-boat is carried, and C C' are davits by which the boat is supported when swung in

outward direction. The davits C C' are supported at their lower ends in deck-plates d d' and brackets e e' at the outer side of the hull B or e² e³ within the hull, the plates d d' being provided each with two holes—one at the inner side and one at the outer side of the hull B and rail D—so that the davits may be mounted either at the inner side of the hull and rail or at the outer side of the same. Upon the deck, between the davits, are arranged two chocks composed of stationary chock-blocks a a' and movable chock-blocks a² a³, said chocks being shaped so as to receive and support the life-boat. The stationary chock-blocks a a' are inclined at their forward side toward the edge of the deck D', as shown in Figs. 4 and 5, so that when the movable chock-blocks a² a³ are released they slide down the inclined portions of the stationary chock-blocks and permit the life-boat A also to descend. For retaining the movable chock-blocks normally in position upon the stationary chock-blocks and also for locking the boat in position upon said chocks, I provide keepers b b' at the rear side of the stationary chocks, respectively, and keepers b² b³ at the forward or front side of the chock-blocks, said forward keepers bearing against and serving to retain the movable chock-blocks a² a³ in position beneath the life-boat. The forward keepers b² b³ are hinged at their inner ends below the inclined portions a⁴ a⁵ of the stationary chock-blocks, so as to be swung in forward or outward and downward direction out of the way of the life-boat and of the movable chocks when the life-boat is to be lowered. The rear keepers b b' may also be hinged at their lower ends, so as to facilitate handling the boat when replacing the same. For retaining the keepers in position I provide a locking mechanism connected with all the keepers, so that all may be simultaneously operated when it is desired to release the life-boat. This mechanism consists principally of two rock-shafts e⁴ e⁵, arranged in the life-boat transversely of the same in suitable bearings and carrying hooks e⁶ e⁷ e⁸ e⁹, one at each end, adapted to engage fastening-links d² d³ d⁴ d⁵, connected with the keepers and projecting through suitable openings in the upper part or rail of the life-boat. To each rock-shaft is connected an operating-

arm projecting therefrom, and said arms $d^6 d^7$ are connected with each other by a cord d^8 . From one of the arms a cord d^9 passes through a suitable opening in the end of the life-boat 5 into position for being grasped and pulled. When the same is pulled, the arm d^7 , to which it is attached, is operated, also the arm d^6 , connected therewith, the rock-shafts $e^4 e^5$ thereby turned and the hooks thereby released 10 from the links, and the life-boat thus freed.

The life-boat is intended to be supported normally in upright position. For protecting the same against rain and the action of the weather, also against the filling of the same 15 with water in a rough sea, a cover E of canvas or other suitable material is provided and means for securing the same over the boat, so as to close the same water-tight, also means for supporting the cover and for releasing the 20 same quickly and reliably when the boat is to be used. The cover extends over the open top of the boat and slightly over the sides of the same and is provided at its edge in suitable hems with two parallel fastening-ropes, 25 which form parallel ridges $f^1 f^2$ with a channel between them, and upon the boat is arranged a fastening-rope f^3 , passing through suitable eyes c and provided in its length with a turn-buckle c'. The fastening-rope f^3 is secured 30 at one end over a pin or stud c^2 at the end of the life-boat and is located when the cover is applied in the channel formed between the fastening-ropes $f^1 f^2$ of the cover. The cover is provided with suitable recesses for accommo- 35 dating the eyes c. For supporting the cover and also for limiting the outward movement of the davits a cover-supporting rod g is provided, which is supported at each end by the davits in suitable swiveled eyes g'. Covering 40 ropes g² are connected at their lower ends with the cover and with the supporting-rod g by suitable rings, so as to slide thereon. By sliding the rings together the flexible cover may be compacted together in folds, so as to expose the ends of the boat, which is of convenience when replacing the boat on the chocks. 45

In order that the weight of the life-boat when released may accomplish the turning of the davits, so that the life-boat is automatically moved from its position of rest into position for launching, the davits are provided each with a suitable drum, which drums g³ g⁴ are preferably located above and adjacent the deck-plates d d'. Over each drum passes 55 a rope connected with the life-boat. The arrangement of the lowering-rope or fall and the davit-rope is shown in detail in Fig. 6. h indicates the lowering-rope or fall, which is secured at one end to the upper end of the 60 davit, passes thence to a pulley-block h', a suspension-pulley h², and a boat-block h³, back through the suspension-pulley h², and thence over a suitable guide-pulley h⁴, preferably arranged on the davit, to a suitable 65 cleat h, also preferably arranged on the davit. To the davit-block h' is attached the davit-rope h⁶, which passes over a second davit

pulley or block h⁷, secured to the vessel, and thence upon the drum g³. The drums g³ g⁴ may be provided with suitable projecting pins g⁵ for retaining the davit-rope h⁶ in position thereon. It will now be observed that when the weight of the life-boat, which is connected by a suitable hook h⁸ with the block h³, is permitted to exert itself upon the said block the lowering-rope or fall h is pulled in the direction indicated by the arrows in Fig. 6, whereby the davit-block h' is drawn and a pull exerted on the davit-rope h⁶, which being transmitted to the drum g³ turns the same, 75 and thereby swings the davit in outward direction. 80

When it is desired to launch the boat, the detachable portion D² of the rail D is removed. The cover E is then released by pulling the rope f³ off from the pin or stud c². This loosens the fastening-rope f³ around the entire life-boat, so that the cover can now be disengaged from the same. The rope d⁹ is now pulled, and thereby the rock-shafts e⁴ e⁵ 90 are turned and the hooks e⁶ e⁷ e⁸ e⁹ released from the links d² d³ d⁴ d⁵. The forward keepers b² b³ being thus released, the movable chock-blocks a² a³, partly by their own weight and partly by the weight of the boat upon 95 them, slide down suitable inclined guides a⁴ of the stationary chock-blocks. For facilitating the downward movement the movable chock-blocks are provided at their under sides with rollers i. The upwardly-projecting guides a⁴ serve for guiding the movable chock-blocks in their descent. The movable chock-blocks swing the forward keepers b² b³ in outward or forward direction, thereby leaving the boat free at its outer side. The boat 100 descends with the movable chock-blocks, being supported partly by the same and partly at its keel upon the guides of the stationary chock-blocks. The boat soon draws the fall h and the davit-rope h⁶ taut, and when the 105 weight of the boat is exerted upon the falls h the outward swinging of both davits simultaneously into position shown in Fig. 3 is caused. The cover E remains supported upon the supporting-rod g. In Figs. 2, 3, and 5 the cover 110 is omitted for clearness. To each movable chock-block is connected a suitable fastening-rope, said ropes h h' being secured at their inner ends to suitable cleats upon the deck D' of the vessel. For imparting to the life-boat a prompt and reliable forward movement two pivoted canting-levers m m' are provided, which are arranged at the rear side of the boat and engage suitable sockets m² m³ of the same and which are located at such a 115 point as to force the boat forward upon its descent, so that it goes forward promptly and in upright position. The boat having been swung forward in the manner indicated, the same is now lowered by paying out the lowering-ropes or falls h. This produces, however, no release of the strain upon the davit-rope, and this is essential in order that the davits should be retained reliably in their 120 125 130

outermost position during the lowering. This result is effected by reason of the fact that the davit-rope is connected by means of its block h' in a bight of the lowering-rope h .

5 The boat having been lowered to the water, the hooks h^s are disconnected from the life-boat, and the latter is free. The falls h may be permitted to remain in lowered position or may be raised again into position shown in 10 Fig. 6.

When it is desired to return the life-boat to its position upon the deck of the vessel, the falls h are lowered and the hooks h^s engaged with the corresponding eyes h^o of the boat.

15 The lowering-ropes are then drawn in, whereby tension is exerted upon the davit-ropes h^o and the davits retained in outward position during the raising of the boat. The boat is raised to a suitable height above the level of 20 the stationary chock-blocks, as indicated in dotted lines in Fig. 5. The releasing-hook m^4 is now opened, thereby disconnecting the upper part of the davit-rope from the lower part. The disconnection of the davit-rope, 25 however, permits the davit to swing freely in any direction, instead of the same being under a constant pull, tending to swing it in outward direction. The upper part l of the davit-rope is now passed through to the other 30 side of the davit, as indicated in dotted lines in Fig. 3. By now simply pulling upon the said ropes $l l$ the davits are swung in inward direction, carrying the boat with them into proper position over the stationary chock- 35 blocks. A suitable block b^4 is provided, against which one end of the boat may abut for locating the same in proper position on the chocks. The movable chocks a^2 a^3 are now raised and placed in position upon the 40 stationary chock-blocks, the forward keepers raised, the boat lowered sufficiently so that the links may be placed in position, and the 45 rock-shafts e^4 e^5 manually turned by means of their arms d^6 d^7 , so that the hooks e^6 e^7 e^8 e^9 engage with the links. The lowering-tackle is now paid out sufficiently so as to permit 50 the upper part l of the davit-rope to be drawn out sufficiently to again engage the releasing-hook m^4 . The turnbuckle c' of the fastening-ropes f^3 is now somewhat loosened, the 55 fastening-rope f^3 engaged with the stud c^2 , the edges of the cover passed beneath said fastening-rope, and the turnbuckle then tightened, thereby securing the cover tightly upon the boat.

Instead of disconnecting the davit-rope h^o for swinging the life-boat inwardly after raising the same, the same may be accomplished in another manner. For this purpose I provide suspension-hooks n , one at each end of the boat, connected therewith by suitable suspension-ropes n' . Each davit is provided at its upper end with a shackle n^3 . The boat having been raised, the suspension-hooks are hooked into the shackles, and the life-boat thereby suspended directly from the davits. The lowering-ropes are now paid out suffi-

ciently to slacken the davit-ropes h^o , and the boat may be then pulled inwardly by sailors upon the vessel grasping the life-boat or a 70 rope thrown out from the boat onto the deck of the vessel. The boat is then lowered into position on the chocks by paying out the suspension-ropes n .

I have illustrated in the drawings pulley-blocks having only a single pulley. This, however, is done merely for the sake of clearness, as the ordinary three-part or four-part blocks will customarily be employed. It is also obvious that in place of the releasing- 80 hook m^4 , which I have shown, any suitable releasing-hook may be employed. The hook shown is operated by simply moving the ring of the same out of engagement with the hook-bar by hand, so that the hook-bar is freed 85 and permitted to turn back so that the rope l passes off the same.

The advantages of my improved apparatus for lowering life-boats are especially the rapidity with which the boat can be launched, 90 the ease with which the launching is effected, the reliable operation of the apparatus, and the fact that only two men are necessary for launching even the largest size of life-boat, whereas heretofore six or seven men were required for the safe launching of boats of the 95 size ordinarily employed.

Having thus described my invention, I claim as new and desire to secure by Letters Patent—

1. An apparatus for lowering life-boats, consisting of two rotatable davits, a drum on each davit, means for supporting the boat on the deck of the vessel, a lowering-rope or fall connected with each davit and with the boat, 105 and a davit-rope for each davit passing over the drum of the same and connected with a bight of said lowering-rope, substantially as set forth.

2. An apparatus for lowering life-boats, 110 consisting of two rotatable davits, a drum on each davit, means for supporting the boat on the deck of a vessel, a lowering-rope or fall connected with each davit and with the boat, a davit-rope for each davit passing over the 115 drum of the same and connected with a bight of said lowering-rope, and means for disconnecting said davit-rope, substantially as set forth.

3. An apparatus for lowering life-boats, 120 consisting of two rotatable davits, a drum on each davit, two stationary chock-blocks located on the deck of the vessel between said davits and provided with a top surface inclined toward the side of the vessel, movable chock-blocks on said inclined top surface, keepers for retaining said movable chock-blocks in position, means for simultaneously releasing both of said keepers, a lowering-rope or fall connected with each davit 125 and with the boat, and a davit-rope for each davit passing over the drum of the same and connected with a bight of said lowering-rope, substantially as set forth.

4. An apparatus for lowering life-boats, consisting of two rotatable davits, a drum on each davit, two stationary chock-blocks located on the deck of the vessel between said davits and provided with a top surface inclined toward the side of the vessel, movable chock-blocks on said inclined top surface, keepers for retaining said movable chock-blocks in position, means for simultaneously releasing both of said keepers, a lowering-rope or fall connected with each davit and with the boat, a davit-rope for each davit passing over the drum of the same and connected with a bight of said lowering-rope, and canting-levers located at the rear side of the boat and adapted to move the same in forward direction during its descent upon said stationary chock-blocks, substantially as set forth.

5. An apparatus for lowering life-boats, consisting of two rotatable davits, means for reasonably supporting the life-boat in raised position adjacent said davits, and means connected with each davit and with the boat, and operated by the latter, for turning said davits while the boat is descending, substantially as set forth.

6. In an apparatus for lowering life-boats, the combination, with keepers arranged at the sides of the boats, and links projecting from said keepers into the boat, of movable hooks mounted within the boat in position to engage said links, and means, extending at the outside of the boat, for simultaneously operating all of said hooks for disconnecting the same from the links, substantially as set forth.

7. In an apparatus for lowering life-boats, the combination, with two rotatable davits,

of a connecting-rod swiveled and slidably connected to the upper ends of both davits, 40 substantially as set forth.

8. An apparatus for lowering life-boats, consisting of two rotatable davits, a drum connected with each davit, two stationary chock-blocks located adjacent said davits, movable 45 chock-blocks adapted to slide in downward direction upon said stationary chock-blocks, keepers for retaining said movable chock-blocks in position, means for releasing said keepers, a lowering-rope or fall connected 50 with each davit and with the boat, a davit-rope for each davit passing over the drum of the same and connected with said lowering-rope, a cover extending over said life-boat and provided at its outer edges with recesses 55 for said keepers, and means securing said cover at its edges tightly to said boat, substantially as set forth.

9. In an apparatus for lowering life-boats, the combination, with two rotatable davits, 60 of a connecting-rod extending between the upper ends of said davits, ropes supporting the life-boat from said davits, a flexible cover for said life-boat, and suspension-ropes connected with said cover and provided at their 65 upper ends with loops or rings adapted to slide upon said connecting-rod so as to permit the compacting together of the cover, substantially as set forth.

In testimony that I claim the foregoing as 70 my invention I have signed my name in presence of two subscribing witnesses.

ANTONIO KERSUL.
